(**) Term: **15 Years**

(57) **CLAIM**

(21) Appl. No.: **29/616,463**

The ornamental design for a foldable insert, as shown and described.

(22) Filed: **Sep. 6, 2017**

DESCRIPTION

(51) LOC (11) Cl. **03-01**

FIG. 1 is a perspective view including a front, bottom and one side of the foldable insert;

(52) U.S. Cl. **D3/319**

FIG. 2 is a perspective view including a rear, bottom and one side of the foldable insert;

USPC **D3/319**

FIG. 3 is a front elevation view of the foldable insert of FIG. 1;

(58) **Field of Classification Search**

FIG. 4 is a rear elevation view of the foldable insert of FIG. 1;

USPC **D3/319**

FIG. 5 is a side elevation view of the foldable insert of FIG. 1;

CPC **A45C 5/14; A45C 7/00**

FIG. 6 is an opposite side elevation view of the foldable insert of FIG. 1;

See application file for complete search history.

FIG. 7 is top elevation view of the foldable insert of FIG. 1; and,

(56) **References Cited**

FIG. 8 is a bottom elevation view of the foldable insert of FIG. 1.
